Primary Examiner—Carol Rademaker

(57) **CLAIM**

The ornamental design for a sidewall for a container, shown and described.

DESCRIPTION

FIG. 1 is a top plan view of the sidewall for a container; FIG. 2 is a front elevational view thereof, the rear elevational view being identical except for the unclaimed threads.

FIG. 3 is a bottom plan view thereof;

FIG. 4 is a bottom front perspective view thereof;

FIG. 5 is a top front perspective view thereof;

FIG. 6 is a left side elevational view thereof; and

FIG. 7 is a planar cross sectional view taken along section line 7—7 of FIG. 6; and,

FIG. 8 is a planar cross sectional view taken along section line 8—8 of FIG. 6.

The broken lines in FIGS. 1-8 are for illustrative purposes only and form no part of the claimed design.
